UNITED STATES PATENT OFFICE

163,790

MOBILE DISPLAY STAND

Maynard A. Buchanan, Omaha, Nebr.

Application December 6, 1950, Serial No. 13,293

Term of patent 3½ years

(Cl. D14—3)

To all whom it may concern:

Be it known that I, Maynard A. Buchanan, a citizen of the United States, residing at Omaha, in the county of Douglas and State of Nebraska, have invented a new, original, and ornamental Design for Mobile Display Stand, of which the following is a specification, reference being had to the accompanying drawing, forming part thereof.

The opposite side and end are similar to those shown in Figures 1 and 2 respectively. The rectangular configuration appearing in Figure 2 of the drawing outlines a recess provided in the end wall of the mobile display stand.

I claim:

The ornamental design for a mobile display stand, as shown and described.

MAYNARD A. BUCHANAN.
